UNITED STATES PATENT OFFICE

112,828

DESIGN FOR A SEWING MACHINE FRAME

Griffith B. Lewis, Watervliet, N. Y., assignor to
Willcox & Gibbs Sewing Machine Company,
New York, N. Y., a corporation of New York

Application November 29, 1937, Serial No. 73,247

Term of patent 14 years

To all whom it may concern:

Be it known that I, Griffith B. Lewis, a citizen of the United States, residing at Watervliet, New York, have invented a new, original, and ornamental Design for a Sewing Machine Frame, of which the following is a specification, reference being had to the accompanying drawings, forming part thereof.

In said drawings, showing a number of views drawn on varying scales,

Fig. 1 is a front perspective view;

Fig. 2 is a rear view;

Fig. 3 is an end view from the left;

Fig. 4 is an end view from the right;

Fig. 5 is a top view; and

Fig. 6 is another front perspective view of a sewing machine frame embodying my design.

What is claimed is:

The ornamental design for a sewing machine frame, as shown.

GRIFFITH B. LEWIS.
